EXTREMELY HIGH-FREQUENCY
ELECTRONIC DEVICE

Winfield W. Salisbury, Cedar Rapids, Iowa, assignor to Collins Radio Company, Cedar Rapids, Iowa, a corporation of Iowa

Application January 23, 1950, Serial No. 140,103

1 Claim. (Cl. 315—6)

1

This invention relates in general to extremely high frequency electronic devices as, for example, between 25,000—500,000 mc.

It is an object of this invention to provide a device for modulating and amplifying a beam of electrons passing through a wave guide.

A further object of this invention is to provide a device in the extremely high frequency range for mixing a plurality of signals.

A feature of this invention is found in the provision for an electron beam producing means which supplies a beam of electrons to a tunable wave guide section into which is coupled an extremely high frequency signal. A tunable receiving wave guide section is mounted in axial alignment with the transmitting wave guide section and an energy coupling means is connected thereto for removing energy at a high power level.

Another feature of this invention is the provision for a plurality of wave guide sections spaced in axial alignment with an energy coupling loop connected to each section and energy removing means withdrawing a mixed signal from a collector electrode.

Further objects, features, and advantages will become apparent from the following specifications and drawings; in which

Figure 1 is a perspective view of the apparatus of this invention illustrating how it may be used as an amplifier; and

Figure 2 is a perspective view of the apparatus of this invention illustrating how it may be used as a mixing device.

Referring to Figure 1, a wave guide section 10 contains therein a slidable shorting member 11. An opening 12 is formed in the member 11 and an electron gun 13, of a kind well known to those skilled in the art, produces a beam of electrons and shoots it through the opening 12 and axially through the wave guide section 10. The slidable member 11 may be adjusted axially of the wave guide by tuning means including the plungers 14 and 16 which are received in a bracket 17. A coupling loop 18 extends downwardly into the wave guide section ahead of the slidable member and furnishes extremely high frequency modulation energy to the wave guide. The slidable member 11 is moved axially of the wave guide until it is tuned to the input frequency from the coupling loop 18. When tuning has occurred, there will be an energy transfer between the input supplied to the coupling loop and the beam of electrons passing axially down the wave guide.

The wave guide 10 terminates in a grid 19 which may comprise, for example, a wire screen. The electron beam passes through the grid into a drift

2

space between the wave guide 10 and a second wave guide 21. The open end of the second wave guide is closed by means of a second grid 20 and the beam passes therethrough. Adjacent the opposite end of the wave guide 21 is a slidable tuning bar 22 which may be moved axially of the wave guide section. An energy coupling loop 23 extends downwardly into the confines of the wave guide section 21 to remove energy therefrom. The tuning bar 22 may be adjusted so that the receiving wave guide 21 is tuned to the sending wave guide 10.

As the electron beams pass through the drift space "bunching" of the electrons occurs and the bunched electrons couple energy to the output loop 23 as they pass thereby. The electron beam impinges on the shorting bar 22 and is removed from the apparatus. A plunger 40 is attached to shorting bar 22.

In order for the wave guide energy transfer device above described to operate, the gain due to the electrons between the input and output loops must be greater than the one-way transmission loss between them. In other words, the feed-back from the output coupling loop 23 must not be so great that the incoming signal fed to the coupling loop 18 is cancelled or reinforced. This condition exists when the wave guides are separated.

If the proper material is used in constructing the wave guide, only one way guide section need be used instead of the two above described. In this case the input coupling loop and the output coupling loop may both be placed within the same wave guide section and the grids 19 and 20 deleted. The transmission loss of the material from which the wave guide is made must be such that the transmission attenuation of the signal is more than the gain of the tube which is equal to the electron gain plus the transmission loss if loss is positive.

The gain of the tube is equal to the electron gain minus the transmission loss. For example, an iron wave guide may have a high enough resistance for this purpose.

- (1) The tube gain is equal to the electron gain minus the transmission loss;
- (2) The electron gain must be greater than the transmission loss; and therefore
- (3) The electron gain is greater than the tube gain.

The above three statements express the necessary conditions for amplification to occur in the tube.

Figure 2 illustrates apparatus which may be

used for mixing a plurality of extremely high frequency signals. A wave guide section 26 has an electron gun 27 slidably mounted therein in a manner similar to that shown in Figure 1. The wave guide 26 terminates in a screen 28 and an input coupling loop 29 furnishes an extremely high frequency input for modulating the beam of electrons from the gun 27. The wave guide section 26 is tuned to the same frequency as the input fed to the loop 29.

Another wave guide section 31 is maintained in axial alignment with the first section 26 and the ends are covered by screens 32 and 33. An input loop 34 feeds a signal into the waveguide 31 which modulates the electron beam passing therethrough. The beam has previously been modulated by the input fed to loop 29 and thus often it passes through the wave guide 31, contains the mixed signals from the inputs 29 and 34.

A collector electrode 36 received the electron beam. As illustrated, the difference frequency ($f_1 - f_2$) may be chosen by connecting the electrode 36 to a circuit 37 timed to the difference frequency. One end of circuit 37 is connected to an external terminal 41. A grounded terminal 42 is mounted adjacent terminal 41. The sum of the mixed frequencies ($f_1 + f_2$) may be obtained by replacing the collector electrode by a wave guide section tuned to the sum frequency. An output loop may remove the energy from the wave guide section.

It is seen that more than two signals may be combined by installing a plurality of wave guide sections in axial alignment and supplying an input to each one. The electron beam may be maintained in focus magnetically or in any other well-known manner.

The plurality of wave guide sections may be replaced by a single wave guide if the three conditions for preventing ring are maintained. This requires that a relative high resistant material be used in the wave guide. The signals to be mixed are fed into the wave guide by means of coupling loops longitudinally spaced along the tube. It is to be realized that the structure of

this invention is enclosed in a suitable envelope 38 which supports the various elements by stand-offs 39. The space within the envelope may be evacuated.

It is seen that this invention provides a mixer and amplifier in the extremely high frequency range and thus makes it possible to use these frequencies in manners that have heretofore been considered impossible.

Although this invention has been described with respect to particular embodiments thereof, it is not to be so limited as changes and modifications may be made therein which are within the full intended scope as defined by the appended claim.

I claim:

An extremely high frequency amplifier comprising a first rectangular wave guide section with a slidable shorting bar mounted therein for longitudinal movement, an electron gun for shooting a beam of electrons through an opening formed in said shorting bar and longitudinally of said wave guide, a second rectangular wave guide section in axial alignment with said first wave guide section for receiving the beam of electrons therein, a collector electrode slidably mounted for longitudinal movement in said second wave guide section, an input loop for coupling energy into said first wave guide section, and an output loop for coupling energy from said second wave guide section.
